Primary Examiner — Rebecca Tsehay

(57) **CLAIM**

The ornamental design for a template for the depilation of the body, as shown and described.

DESCRIPTION

FIG. 1 is a perspective view of the claimed design in use on a person's eyebrow region.

FIG. 2 is a front view of one embodiment of the claimed design.

FIG. 3 is a front view of another embodiment of the claimed design; and,

FIG. 4 is a front view of yet another embodiment of the claimed design.

The broken lines in the drawing figures depict environmental subject matter and form no part of the claimed design.
